UNITED STATES PATENT OFFICE.

WILLIAM MORRISON, OF TORONTO, ONTARIO, CANADA.

HOT-AIR FURNACE.

SPECIFICATION forming part of Letters Patent No. 376,390, dated January 10, 1888.

Application filed April 14, 1886. Renewed May 14, 1887. Serial No. 238,287. (No model.)

To all whom it may concern:

Be it known that I, WILLIAM MORRISON, of the city of Toronto, in the county of York, in the Province of Ontario, Canada, manufacturer, have invented an Improved Hot-Air Furnace, of which the following is a specification.

The object of the invention is to design a sectional heater in which the greatest possible heating surface is obtained, and which may be adapted for hot air, hot water, or steam, or hot air and steam, or hot water and hot air combined; and it consists in the peculiar construction and arrangement of parts, all as more fully hereinafter described and claimed.

Figure 1 is a perspective view of my improved heater, partially in section, exhibiting it as a combined hot-air and hot-water or hot-air and steam heater. Fig. 2 is a plan of a steam or hot-water section. Fig. 3 is an elevation, partially in section, showing the manner of connecting the sections together. Fig. 4 is a partial plan of a hot-air section. Fig. 5 is an alternative form of the same.

In the drawings like letters of reference indicate corresponding parts in each figure.

A represents the cold air duct leading into the space between the outer shell, B, and the heater proper.

C represents the hot-air flues, from which the heated air is conveyed to the different parts of the house.

D is the hot-water or steam pipe leading from the top section, E, to the coils in the house.

F is the return-pipe connecting the coils with the bottom hot-water section.

G is a smoke-pipe which extends through the top section, E, as indicated.

In Fig. 1 I show the four lower sections, H, I, J, and K, made to constitute what I may term "hot-air sections." These consist of tubes a, extending clear through the section and having open ends to communicate with the space between the heater and the outer shell, B. It will be noticed that the tubes in the section I are placed at right angles to the tubes in the section H, and that the tubes in K are at right angles to the tubes in J. In other words, the tubes in one section are at right angles to the tubes next to them, as indicated by Figs. 4 and 5. These sections H,

I, J, and K may be held together by simple sand or other suitable joints designed to prevent the escape of gas, as indicated in Fig. 3, 55 as there is no pressure to disturb them; but the sections L, M, N, and O must be securely bolted together by the bolts P, one of which is located at each corner of the sections, which are composed of a series of tubes, b, which, 60 instead of extending entirely through the sections, lead into a rectangular chamber, D', extending completely around the section, as indicated.

In order to form joints between the sections 65 L, M, N, and O, and at the same time connect them all together, I form an open ring, Q, through which the bolts P pass, and the surfaces of which coming in contact with each other form a face-joint between each section. 7c

I may here mention that instead of the common sand joint represented in Figs. 3 and 4, the sections H, I, J, and K may be provided with joints similar to that shown in Fig. 2. This is suggested by Fig. 5.

The top section, E, is a chamber extending completely across the heater, and with which chamber the steam or water sections L, M, N, and O communicate, so that when the heater is used as a steam-heater the steam accumulates in the chamber formed in the section E, or when they are to be used as hot-water sections a large body of water is held in the section E, to be drawn upon by the pipe D.

By placing the tubes alternately at right 85 angles to each other the ascending heated gases are, as it were, broken in passing between the tubes, thus causing each tube to be encircled, and thereby securing a maximum of heating or fire surface to a minimum of grate-surface. 90

A further advantage I secure by setting the tubes as mentioned is the facility with which their outside surfaces may be cleaned.

What I claim as my invention is—

1. The combination, with the fire-chamber, 95 of a plurality of hot-air sections, H I J K, each provided with open-ended tubes, but distinct from each other, arranged above said fire-chamber, a plurality of water-sections, each communicating with the other and superimposed upon said hot-air sections, and a shell surrounding said sections, substantially as and for the purpose specified.

2. The combination of the communicating

- sections L M N O, each comprising a rectangular surrounding tube, a plurality of transverse tubes opening into the surrounding tube and an opening at each corner, the top section, 5 E, forming a steam or water chamber, the outlet-pipe D, communicating with the top section, the inlet-pipe F, communicating with the lowest section, O, and a surrounding shell, substantially as described.
- 10 3. The combination, with the fire-chamber, of the sections H I J K, constructed, as described, with transverse tubes at each end, each section distinct from the other and arranged above said fire-chamber, the communicating sections L M N O, superimposed upon said sections, a section, E, above said sections L M N O and forming a water or steam cham-

ber, and an outer shell surrounding said sections, substantially as described.

4. The combination, with the outer shell, B, 20 and the hot-air sections H I J K, and closed communicating water-sections L M N O, superimposed thereon, of the water-section E above the water-sections and communicating therewith, the smoke-pipe G, extending through 25 the section E, the return-pipe F, connected with the lower water-section, and the steam-pipe D and hot-air flues C, substantially as and for the purpose specified.

Toronto, February 17, 1886.

W. MORRISON.

In presence of—

CHARLES C. BALDWIN,
JAMES E. MAYBEE.
